DRAGLINE EXCAVATOR

Oscar J. Martinson, Chicago, Ill., assignor to
Bucyrus-Monighan Company, Chicago, Ill., a
corporation of Illinois

Application October 17, 1938, Serial No. 235,420

14 Claims. (Cl. 37—116)

This invention relates to dragline excavator equipment, and the purpose of the invention is to extend the reach or operating range of any dragline excavator of customary construction without necessitating a change of the point of application of lift on the boom of a loaded bucket. The purpose of the invention is attained by a modification in rigging wherein the main boom has an extension boom attached thereto without interfering with the normalcy of the rest of the rigging; that is, a hoist line as usual passes from the bucket over a sheave at the end of the main boom, and the dragline extends from the bucket to operating means in the base-supported machinery. There is, however, in the new construction a second hoist line which leads from the bucket around a sheave at the outer end of the extension boom. The function of this second hoist line is to carry an unloaded bucket outwardly away from the machine further than is possible with the normal boom length and without necessity for this hoist line sharing in the lift or support of a loaded, suspended bucket.

A secondary object of the invention is the provision of an improved double hoisting drum unit particularly adapted for this extended boom arrangement.

The drawings illustrate the invention diagrammatically as to the general layout and in detail in reference to the mounting of the extension boom and to winding drums particularly designed for controlling the action of companion hoist lines:

Figure 1 is a diagram showing the improved dragline excavator in side elevation.

Fig. 2 shows in longitudinal section a pair of winding drums for hoist lines.

Fig. 3 is a sectional view on the line 3—3 of Fig. 2.

Fig. 4 is a fragmentary side view of the main and extension booms showing their pivot connection.

Fig. 5 is another side elevation like Fig. 1 of the improved dragline excavator, but differs from Fig. 1 in showing that one of the cables by which the bucket is suspended leads to a counter-weighted drum to give this line an automatic action in taking up slack.

Fig. 6 is a plan view of the cable winding unit used in the construction shown by Fig. 5.

Fig. 7 shows the winding unit of Fig. 6 in side elevation.

Fig. 8 is a plan view of the treadle mechanism for pneumatic control of the brakes for the winding drums shown in Figs. 6 and 7.

Fig. 9 is a side view of the treadle mechanism. Figs. 10 and 11 are details of the treadles and

Fig. 12 is a diagram of a simplified control means for the extra suspension line which leads from the bucket to the extension boom.

The type of dragline excavator to which the improvements are here shown as applied is of the familiar kind using a main supporting base for resting upon the ground and upon which is supported for rotation on a vertical axis a heavy machinery supporting platform. The boom is pivoted on a horizontal axis to the platform which also carries a mast structure. Boom supporting suspension cables or stays extend between the mast and the boom. These principal elements of the dragline excavator are indicated on the drawings as follows:

Main base 1	
Machinery supporting platform 2	20
Mast 3	
Boom 4	
Suspension cables 5	
Drag bucket 6	
Dragline 7	15
Bucket hoist line 8	25

Sheaves are located where necessary and the lines are doubled back and forth between the sheaves when required to reduce the strain on the cables.

Improvement of that standard construction is indicated on the drawings as follows:

The particular double hoist line winding drum unit of Figs. 2 and 3, or the one of Figs. 6 and 7.

Extension boom 10.

A journal or pivot bearing connection 11 between the outer end of the main boom and the extension boom.

Suspension cables 12 between the extension boom 40 and the mast.

A sheave 13 at the outer end of the extension boom.

A hoist line 14 leading from the bucket to the extension boom sheave and from there to a winding drum on the machinery platform.

And control means for cable winding drums including an independent or dependent automatic control for the additional hoist or bucket suspension cable added to the rigging because of the extension boom requirements.

The two hoist lines 8 and 14 are operated by means of a power-driven drum unit as indicated in detail by Fig. 2, or by Figs. 6 and 7. In Fig. 2, 55

the hoist line 8 is anchored to drum 15 and the hoist line 14 is anchored to drum 16. A common drive for the two drums is driven gear 17, and this gear is clutched as required to the drum 15 through clutch 18.

The drum supporting shaft 19 is journalled in bearings at 20 and 21, and the drum 16 is freely rotatable on the shaft. This drum is frictionally driven from the direct driven drum 15 through friction clutch shoes 22. Springs 23 provide the necessary contact pressure between the shoes and the drum flange. Differential rotation of the two drums is controlled by use of brakes, brake for drum 15 being represented at 24, and brake for drum 16 being represented at 25.

The pivot mounting of the extension boom 10 on the outer end of the main boom 4 is detailed in Fig. 4. This figure also indicates the customary hoist line sheave 26 journalled near the end 20 of main boom 4, and the bucket is as usual suspended from sheave 26 and hoisted when loaded by means of the hoist line 8 passing over the sheave to drum 15.

The dragline 7 is also operated as usual by a winding drum 27, Fig. 1, and leads from this drum between fair-leaders 28 and 29 at the front end of platform 2 around a block 30 to the attachment point 31 above the mouth of the bucket. The dragline 7 is connected by chain 32 to the forward end of the bucket below the attachment point 31. The shell or housing of block 30 is connected by chains 33 with trunnions 34 toward the rear of the bucket. The bucket ends of hoist lines 8 and 14 are also attached to the housing of block 30. With that arrangement, whenever there is sufficient tension on the dragline 7, the bucket is held in its horizontal position and prevented from assuming the unloading vertical position, and this is a common rig for drag buckets 40 with the exception that it is not customary to use two hoist lines.

In the improved construction the customary hoist line 8 is supplemented by hoist line 14, and the purpose of hoist line 14 which leads over the outer end of the extension boom 10 is to enable an unloaded bucket to swing outwardly around a center provided by sheave 13 rather than around the center provided by sheave 26. The normal reach of the machine is thus increased; for example, if the main boom is 100 ft. or so in length, the extension boom 10 may be proportioned thereto, as indicated in Fig. 1, to increase the reach nearly one-third. Therefore, the function of this extension boom is for increasing the operating range of the excavator by carrying an empty bucket further out, and may be left free of sharing the load of a filled bucket in lifting the loaded bucket and carrying it to the dumping position, as the machine swings on a central axis provided by main base 1.

The operation of the machine, without reference to the extension boom and the added hoist line, is as usual carried on by first paying out on hoist line 8 to lower the bucket to the point where it begins the inward filling stroke toward the machine, which inward stroke is effected by winding up the dragline 7 on drum 27. Then while the bucket is lifted by winding up hoist line 8 on drum 15, dragline 7 is paid out, but with tension maintained thereon to prevent the bucket from unloading until the machine is swung over to the unloading position when the unloading occurs automatically by relieving tension on line 7. Then the cycle is repeated by swinging the machine back toward working position and paying

out on both lines 8 and 7 to place the bucket for a new filling stroke.

With the improved construction the customary operation may be altered by, after unloading the bucket, effecting a differential paying out of hoist lines 8 and 14, whereby the bucket may be swung outwardly from both the pivots provided by sheaves 26 and 13, or exclusively around the pivot provided by sheave 13. The bucket is thus placed outwardly further than it could be with 10 normal boom length. The total support required from the extension boom is that of the weight of the unloaded bucket. The extension boom may therefore be of relatively light construction. After the completion of the lengthened digging 15 stroke the main boom takes all the load of lifting the loaded bucket through hoist line 8.

The differential winding up and paying out of the hoist lines 8 and 14 is effected by use of brakes 24 and 25, Fig. 2. When drum 15 is used 20 to lift the loaded bucket it must take the load of lifting because of the positive drive with which it is provided, whereas drum 16 may merely take up the slack in hoist line 14 because of the slip drive 22 between the two drums. After the bucket is unloaded, it may be held suspended under sheave 26 by the use of brake 24 to prevent reverse or unwinding turning of drum 15, or it may be swung further outwardly from sheave 13 as a pivot by releasing brake 24, while holding with 25 brake 25. Then to lower the bucket to the extreme outer position to begin a new stroke both lines are relieved; or, if it is desired to place the bucket inwardly from that position, the brakes 30 may be used differentially. The friction clutches 22 prevent any back spinning of drum 16 over drum 15, whether the brake 25 is used or not.

The foregoing description with reference to Figs. 1 to 4 of the drawings relates to the general arrangement and purpose of the improvement. 40 Figs. 5 to 11 serve to amplify the illustration in regard to control of the winding drums, and in regard to provision of automatic means for taking up the slack in cable 14. This cable has been referred to as hoist line because it supplements the actual hoist line 8 but the function of line 14 is mainly to provide an additional suspension means for an unloaded bucket whereby the bucket may be swung outwardly from a point located further out than the normal location of sheave 26 for the hoist line 8. Such performance may take place when the brake is released on winding drum 15 for hoist line 8. Then, by releasing dragline 7 the bucket swings outwardly around sheave 13 and is lowered more-or-less as 50 required in the work, according to the release or application of the brake for drum 16.

The brake control means for drums 27, 15 and 16, as illustrated in Figs. 8 to 11, include control cylinders 35, 36 and 37 having pistons connected with treadle mechanism whereby air or hydraulic pressure may be transmitted through the conduits 38, 39 and 40 to brake actuating cylinders 41, 42 and 43. The brake actuating cylinders are connected through their pistons to brake band 65 actuating levers 44. The brake bands 45, 46 and 47 are indicated in Fig. 7 and used respectively on the brake drums 48, 49 and 50 of the winding drums 16, 15 and 27.

Drums 15 and 27 are driven through friction 70 clutches 51 and 52 through the drive gearing 54. Drum 16 is driven either by the weight of the bucket through cable 14, or in the opposite direction to take up slack in cable 14 by a counter-weight 55, Fig. 5. This counterweight moves up 75

and down in guide channels 56 and is connected through a cable 57 to a small winding drum 58. Drum 58 has a gear connection 59 with drum 16. All control cables for the bucket are anchored to their respective drums.

The treadle arrangement shown by Figs. 8 to 11, includes a drag brake pedal 60, and a combination pedal 61 for the hoist line 8 and the extra suspension line 14. The pedal 60 operates the piston of cylinder 35 and the pedal 61 operates either or both of the pistons for the cylinders 36 and 37. If pedal 61 is stepped on centrally, both of brakes 46 and 45 are applied. If the left end of the pedal is stepped on only brake 46 will be applied and if the right end of the pedal is stepped on, only brake 45 will be applied; by sliding the foot to the right or left one or the other of the brakes will be favored. Thus, differential action between the brakes is easily attained. To allow for lateral tilting of pedal 61, it is mounted on the cylinder actuating levers as indicated by Fig. 10. Pedal 61 is pivoted on the levers by ears depending from the pedal and one of these ears has an elongated slot through which one of the levers passes and thus allows for lateral tilting of pedal 61.

In the operation of the construction shown in Figs. 5 to 11, if there is no requirement for using the extension boom the control of the bucket is exclusive through drums 27 and 15 which respectively operate the dragline 7 and the hoist line 8. The cable 14 which swings from sheave 13 then merely has an idle action being drawn along in one direction by the weight of the bucket when it is lowered, and when the bucket is raised by winding up hoist line 8, the slack in line 14 is taken up by the counterweighted drum 16. Brake band 45 is off under such conditions.

The operation with an increased reach varies from normal merely by making use of cable 14 so as to swing an unloaded bucket outwardly further than normal by making use of brake 45. By stepping on the right end of pedal 61 brake 45 is applied more-or-less while brake 46 is relieved. Then the bucket swings outwardly from the sheave 13, the brake 47 for the dragline at that time being relieved. The bucket is lowered by relieving brake 45 and brake 46 and, by a differential use of these brakes, may be placed for the maximum reach, or less. The maximum reach is attained by what is termed casting; that is, permitting the bucket to swing outwardly by its own weight beyond the location of the boom sheaves, and then lowering in timed relation with the swing.

The control means illustrated by Fig. 12 is a simplified arrangement for effecting automatic action in swinging the bucket outwardly from the extension boom. In the arrangement shown by this figure, a single pedal 62 takes the place of the compound pedal arrangement 61 of Fig. 8. Pedal 62 controls the winding drum 15 for hoist line 8, Fig. 5, in the normal manner, as it does in this type of machine when not equipped with an extension boom.

The normal function of hoist line 8 is to lift loaded or unloaded buckets and also to control their digging angle when drawn toward the machine by the dragline. In Fig. 12 this pedal is shown equipped with a switch-actuating foot rest 63. Thus, when the pedal is depressed in the normal operation of the machine, the element 63 serves to close a brake-actuating switch 64. The brake 65 controlled by this switch serves to place a measured resistance on drum 16 for bucket line 14

leading over the extension boom. Switch 64 is normally held open by a spring, but when the circuit 66 is closed by the switch, a magnetically-operated valve 67 is opened to admit air to a brake-actuating cylinder 68.

The air supply comes from conduit 69 and passes through a reducing valve 70 before reaching valve 67. Adjustment of the reducing valve controls the maximum pressure admitted to cylinder 68 and thus the resistance afforded by brake 65 is under control. The counterweight cable 57 is connected through gearing 59 the same as in Fig. 5, with the drum 16 tending always to keep any slack from occurring in cable 14. Cable 14 is overhauled or mildly tensioned by the effect of the counterweight. It unwinds due to the weight of the empty bucket, but by the application of brake 65, the needed resistance to unwinding of cable 14 is afforded to cause the bucket to swing outwardly from the sheave 13 as a center, according to the extent that line 8 is permitted to reeve out from its winding drum.

The extent of depression of pedal 62 determines the degree of application of the brake to hoist line winding drum 15, as illustrated by Figs. 7 and 8. When loading the bucket brake 65 is off and cable 14 is free to run except that it is overhauled by the counterweight to keep free of slack.

Accordingly, the operation of the control means shown by Fig. 12 is incidental to the normal operation of the machine, as though it had no extension boom, but with the extension boom and the equipment shown by Fig. 12 when the hoist line 8 is permitted to reeve out for the purpose of lowering the bucket, the winding drum 16 is caused by the friction brake to lag behind the rotation of drum 15 and thus permit the hoist or suspension line 14 to function and cause the bucket to swing outwardly to the end of the extension boom. The brake 65 is set so as to be at all times insufficient with the aid of the counterweight to overcome the weight of the unloaded bucket. Accordingly, by paying out on cable 8 as usual, the bucket lowers but the resistance of the brake and the counterweight connected with cable 14 is sufficient to cause the bucket to swing from sheave 13, as a center, Fig. 5.

I claim:

1. A dragline excavator comprising a base structure having mounted thereon operating machinery, a mast supported by the base structure, a main boom supported at one end on said structure, an extension boom supported at one end on the outer end of said main boom, suspension stays between the mast and said booms for regulating the diagonal setting of the booms with reference to the base and the alinement of the booms with each other, dragline equipment comprising a bucket and operating lines therefor including a dragline and a hoist line, the hoist line leading from the bucket to the outer end of the main boom and from thence to the operating machinery, and a second hoist line leading from the bucket over the end of the extension boom and from there to the operating machinery.

2. A dragline excavator comprising a base structure having mounted thereon operating machinery, a mast supported by the base structure, a main boom supported at one end on said base structure, an extension boom supported at one end on the outer end of said main boom, suspension stays between the mast and said booms for regulating the diagonal setting of the booms with reference to the base and the alinement of the booms with each other, dragline equipment com-

- prising a bucket and operating lines therefor including a dragline and a hoist line, the hoist line leading from the bucket to the outer end of the main boom and from thence to the operating machinery, and a second hoist line leading from the bucket over the end of the extension boom and from there to the operating machinery, and a pair of winding drums for the hoist lines, a common drive for said winding drums, said drive including a clutch, a friction connection between the two drums whereby one may drive the other with slip, and a brake for each of said drums.
3. A dragline excavating machine equipped with a main boom and an extension boom pivoted to the main boom, a dragline bucket with a pair of hoist lines by which said bucket is suspended from the end of the main boom and from the end of the extension boom, a double winding drum unit for said hoist lines, means for operating said drums differentially, and a dragline for the bucket with operating means therefor.
4. A dragline excavating machine equipped with a main boom and a separate extension boom attached to the main boom, said extension boom being of lighter construction and having less carrying capacity than the main boom, a dragline bucket with a pair of hoist lines by which said bucket is suspended from the end of the main boom and from the end of the extension boom, a double winding drum unit for said hoist lines, means for operating said drums differentially, and a dragline for the bucket with operating means therefor.
5. A dragline excavator having a main boom and an extension boom pivoted to the main boom with suspension means for each of said booms, a dragline bucket, a pair of hoist lines for said bucket, one of said lines leading to the main boom and the other of said lines leading to the extension boom, and a winding drum unit having a provision for differentially operating said hoist lines.
6. A dragline excavating machine provided with a main boom and a separate extension boom mounted on said main boom, said extension boom being of lighter construction and having less carrying capacity than the main boom, each of said booms having a sheave at its outer end, a drag bucket, a dragline secured to the bucket, a pair of bucket suspension lines extending from the bucket over said sheaves, operating means for said suspension lines including differentially operable members for taking up and paying out said lines.
7. A dragline excavating machine provided with a main boom and an extension boom mounted on said main boom, each of said booms having a sheave at its outer end, a drag bucket, a dragline secured to the bucket, a pair of bucket suspension lines extending from the bucket over said sheaves, operating means for said suspension lines, including differentially operable members for taking up and paying out said lines, a control for said operating means including a treadle mounted for variable differential action, and motion transmitting connections between said treadle and the operating means.
8. A dragline excavating machine provided with a main boom and an extension boom mounted on said main boom, a sheave at the outer end of each of said booms, a drag bucket, dragline operating means on said machine with a dragline connection to the bucket, a pair of bucket suspension lines extending from the bucket over said sheaves, operating means for

each of said suspension lines including a counterweight for taking up the slack on one of said suspension lines.

9. A dragline excavating machine provided with a main boom and an extension boom mounted on said main boom, said extension boom being of lighter construction and having less carrying capacity than the main boom, a sheave at the outer end of each of said booms, a drag bucket, dragline operating means on said machine with a dragline connection to the bucket, a pair of bucket suspension lines extending from the bucket over said sheaves, winding drums for the dragline and each of said suspension lines, power means for driving the dragline drum and for driving one of said suspension line drums, a control for said power means for operating said driven drums together or separately, and means for varying the resistance of the other suspension line winding drum coincidental with the action of the power-driven suspension line drum.

10. A dragline excavating machine provided with a main boom and an extension boom mounted on said main boom, said extension boom being of lighter construction and having less carrying capacity than the main boom, a drag bucket, suspension means for the drag bucket connected with the main boom, a separate suspension means for the drag bucket connected with the extension boom, control means for actuating said first-mentioned suspension means, and a control for said second suspension means arranged for independent action or for operation in unison with the action of said first-mentioned control.

11. A dragline excavating machine provided with a main boom and an extension boom mounted on said main boom, a drag bucket, cable winding means on said machine with three cables leading to the bucket, one of said cables extending direct from the machine to the bucket, another of said cables extending from the machine to the bucket over a sheave on the main boom, and another of said cables extending from the machine to the bucket over a sheave on the extension boom, the winding means for said extension boom cable being arranged to partly counterbalance the weight of the bucket, means for adding resistance to said counterbalanced winding means and comprising an air-actuated brake, means for controlling the operation of the winding means for the bucket suspension cable passing over the main boom, and said control means being associated with a cooperative control for the bucket suspension cable passing over the extension boom.

12. A dragline excavating machine comprising a boom supporting structure, a boom mounted thereon, a drag bucket, hoisting means extending from the end of said boom to the bucket, and dragline equipment for effecting the filling motion of the bucket; in combination with an extension boom coupled to the main boom, said extension boom being of lighter construction and having less carrying capacity than the main boom, bucket suspension means extending from the extension boom to the bucket, and manually controllable operating equipment for the hoisting means and the suspension means arranged for transferring part of the load of an empty bucket from the hoisting means to the suspension means.

13. A dragline excavating machine comprising a boom supporting structure, a boom mounted thereon, a drag bucket, hoisting means extending

from the end of said boom to the bucket, and dragline equipment for effecting the filling motion of the bucket; in combination with an extension boom coupled to the main boom, said extension boom being of lighter construction and having less carrying capacity than the main boom, bucket suspension means extending from the extension boom to the bucket, and operating equipment for the hoisting means and the suspension means arranged for transferring part of the load of an empty bucket from the hoisting means to the suspension means.

14. A dragline excavating machine having a boom construction provided with a pair of widely

spaced sheaves lengthwise of the boom, a base for supporting the boom, said boom being of relatively lighter construction at the portion between the sheaves than between the inner sheave and the base, a drag bucket, a dragline extending from the base to the bucket, a pair of bucket suspension lines extending from the base over said sheaves to the bucket, and operating means on the base for winding up said suspension lines and arranged to cause the line passing over the inner sheave to carry the major weight of a loaded bucket and the other suspension line to take less than the full weight of an unloaded bucket

OSCAR J. MARTINSON.
